GESELLSCHAFT, WERNERWERK, OF SIEMENSSTADT BEI BERLIN, GERMANY.

TELEPHONE SYSTEM.

Application filed April 3, 1926, Serial No. 99,432, and in Germany April 16, 1925.

This invention relates to telephone systems in general, but is more particularly concerned with the transmission of current impulses over trunk lines in telephone systems, 5 in which direct current impulses are repeated by induction over a trunk line inductively coupled up at both ends. The instant case may be considered as an improvement on the system described in German application 10 S. 69124 VIII/21^a, in which the repeated impulses are received by a polarized relay at the incoming end of the trunk line. This invention relates to a further development of this arrangement, and its object is to render the 15 impulse receiving devices more simple. According to the invention, this is achieved by an arrangement wherein a relay, which acts as an impulse receiving relay responding to direct current, has its energized condition 20 altered by the induced impulse, which is generated at the repeating point at the commencement of an impulse, and the said relay is returned to its normal position by the induced impulse at the end of the impulse.

25 The Figures 1 to 4 show one method of carrying out the invention, but only those circuits and devices are shown, that are required for understanding the invention.

The method of operating the arrangement 30 will now be further described with reference to the Figures 1 to 4.

The Figure 1 shows a trunk line VL having its two ends inductively coupled to the impulse sending and impulse receiving devices by means of the repeaters Ue 1 and Ue 2. After the trunk line has been taken into use in some known manner, the relay A (Figure 1) is operated according to the number of current impulses transmitted by a calling 35 station. At its contacts 1 a and 2 a, the relay A closes a circuit over the left hand winding of the repeater Ue 1. In the right hand winding of this repeater an induced current impulse is generated in a particular direction, i. e., of particularly polarity; this induced impulse goes over the leads VL a and VL b of the trunk line taken into use and reaches the left hand winding of the repeater Ue 2 at the incoming end of the trunk line. 40 As a result, an induced current impulse is generated in the right hand winding of the repeater and it passes over the winding I of the impulse receiving relay J. The latter relay, at its contact 3 j, closes the following 45 circuit; earth, contact 3 j, winding of the

current impulse repeating relay H, winding II of relay J, battery, earth. At its contact 4 h, relay H transmits an impulse over the upper talking lead of the incoming trunk line to the positioning mechanism of the 60 succeeding connecting devices, while a locking circuit for relay J is closed over its winding II. At the end of the current impulse, the relay A at the outgoing end of the trunk line falls back, and at its contacts 1 a and 2 a it interrupts the direct current flowing over the left hand winding of the repeater Ue 1. Thus, an induced current impulse is generated in the right hand winding of Ue 1, the 65 direction of which is opposite to the direction of the current that was first induced. This opposing induced impulse reaches the winding I of the relay J over the repeater Ue 2. The windings of the relay J are now 70 traversed by currents in opposite directions; hence relay J falls back and at its contact 3 j opens the circuit of relay H. At the contact 4 h a current impulse was transmitted of the same duration as that received by the relay A at the outgoing end of the trunk line. 75 The succeeding current impulses received by the relay A cause the same circuit changes, so they need not be further described.

The induced impulse, which is generated by interrupting the direct current circuit 80 over the left hand winding of the repeater Ue 1, is of very short duration, and in order to effect the release of the impulse receiving relay J in a reliable manner the induced impulse, generated at the end of the current 85 impulse, can be artificially lengthened. This is effected by damping devices, for example, resistances, inductances and capacities, which are inserted in the direct current circuit, that is closed over the winding of the repeater 90 Ue 1. The Figures 2 and 3 show two arrangements for this purpose.

In the Figure 2 the winding of the repeater is connected in parallel with a resistance W', a choke coil Dr', and a condenser C'. These allow the energy stored in the repeater winding to be slowly discharged when the direct current circuit is opened. The induced impulse, which is generated at the end of a current impulse, 100 is prolonged by this arrangement. This ensures the reliable release of the impulse receiving relay J.

In the Figure 3 these equalizing devices, instead of being connected in parallel with 110

the repeater winding, are only connected thereto over the back contacts 7 a' and 8 a' when the relay A' falls back. The same effect is produced as by the arrangement shown in the Figure 2.

However, the speech currents are weakened by the clamping devices bridged across the speaking leads, it is therefore advisable to disconnect this arrangement from the trunk line during conversation. This can be effected by contacts of relays (not shown) which are connected up in some known manner at the commencement of the conversation. The Figure 4 shows another arrangement, whereby the weakening of the speech currents by the damping devices can be prevented. The direct current circuit for generating the induced impulses is bridged across the outgoing end of the trunk line over a special repeater Ue 3. When the relay A1 operates, its contact 9a 1 closes a direct current circuit over the left hand winding of the repeater Ue 3. An induced impulse is thereby generated in the right hand winding of the repeater Ue 3 and reaches the left hand winding of a speaking current repeater, the right hand winding of which is connected to the trunk line taken into use. During the impulse transmission, the same operations take place as those described with reference to the Figure 1. It is not necessary to disconnect the damping devices W, Dr and C, because they are only inductively coupled to the speaking leads and can therefore cause no appreciable weakening of the speech currents.

When the current impulses are transmitted over long lines, the transmitted induced current is so weak that the operation of the impulse receiving relay to connect up its holding winding over its own front contact is delayed. The closing of this direct current circuit over the holding winding II induces an impulse in the energizing winding I, the direction of this induced impulse being opposite to that of the induced impulse that energized the relay. The magnetizing strength of the impulse receiving relay is therefore proportional to the difference between the strength of the two induced currents. If the induced impulse that energizes the relay be weakened by the length of the trunk line, it may happen as a result that the relay does not become sufficiently magnetized to keep its armature attracted. This defect can easily be removed by means of the circuit shown in the Figure 5. The impulse receiving relay J, Fig. 1, has its winding I energized by the induced impulse at the commencement of an impulse. The relay closes its contact 3j, thereby establishing the following holding circuit for the winding II': earth, contact 3j, winding II' of relay J, contact h', winding of the relay H, battery, earth. The cur-

rent flowing over this circuit is comparatively strong, so that even though the energizing current impulse be very weak, the armature 1 will be held in a reliable manner. The follow-up contact h is opened shortly after the auxiliary relay H' has been operated, thus the resistance W 1, which hitherto has been short circuited, is placed in the locking circuit of the relay J. The strength of the current in the holding circuit is thereby reduced in order to demagnetize the impulse receiving relay J in a reliable manner when the winding I of relay J is energized by the induced impulse arriving at the end of the current impulse.

What is claimed is:

1. In combination, an impulse transmitting relay having a first and a second winding, means for producing a current flow in one direction in said first winding for operating said relay to close a locking circuit for itself including said second winding, means for producing a current flow in the other direction in said first winding to de-energize said relay, said locking circuit being opened thereby, and means controlled by said relay for transmitting digit impulses.

2. In a telephone system, a trunk line divided into sections inductively coupled, means for producing a direct current impulse in the outgoing section, said impulse causing two impulses in said incoming section, and a relay in said incoming section responsive to said first impulse to close a locking circuit for itself and responsive to said second impulse to open said locking circuit.

3. In a telephone system, a trunk line divided into sections inductively coupled, means for producing a direct current impulse in the outgoing section, said impulse causing a first induced impulse current in one direction and a second induced current impulse in the other direction in the incoming section, an impulse repeating relay, and an impulse receiving relay responsive to said first induced current impulse to close a circuit for said impulse repeating relay and responsive to said second induced impulse to open said circuit.

4. In a telephone system, a trunk line divided into sections inductively coupled, means for momentarily causing a direct current flow in the outgoing section causing an induced impulse of one nature in the incoming section at the start of said direct current and an induced impulse of a different nature at the termination of said direct current in the incoming section of said trunk line, an impulse repeating relay, and an impulse receiving relay responsive to said first induced impulse to close a circuit for said impulse repeating relay and responsive to said second induced impulse to open said circuit.

5. In a telephone system, a trunk line di-

vided into sections inductively coupled, means for producing a direct current impulse in the outgoing section, said impulse causing a first induced impulse current in one direction and a second induced current impulse in the other direction in the incoming section, an impulse repeating relay, and an impulse receiving relay responsive to said first induced current impulse to close a circuit for said impulse repeating relay and responsive to said second induced impulse to open said circuit.

6. In a telephone system, a trunk line divided into sections inductively coupled, means for producing a direct current in the outgoing section of the trunk line, means for momentarily causing an induced impulse of one nature in the incoming section at the start of said direct current and an induced impulse of a different nature in the incoming section at the termination of said direct current in the outgoing section of said trunk line, an impulse repeating relay, an impulse receiving relay responsive to said first induced impulse to close a circuit for said impulse repeating relay and responsive to said second induced impulse to open said circuit, and damping means in the outgoing section for causing the two induced impulses in the incoming section to be of similar nature though opposite in direction.

7. In a telephone system, a trunk line divided into sections inductively coupled, means for producing a direct current impulse in the outgoing section, said impulse causing a first induced impulse current in one direction and a second induced current impulse in the other direction in the incoming section, an impulse repeating relay, an impulse receiving relay responsive to said first induced current impulse to close a circuit for said impulse repeating relay and responsive to said second induced impulse to open said circuit, damping means in the outgoing section for causing the two induced impulses in the incoming section to be of similar nature, and means for disconnecting said damping means.

8. In a telephone system, a trunk line divided into sections inductively coupled, means for producing a direct current in the outgoing section of the trunk line, means for momentarily causing an induced impulse of one nature in the incoming section at the start of said direct current and an induced impulse of a different nature in the incoming section at the termination of said direct current in the outgoing section of said trunk line, an impulse repeating relay, an impulse receiving relay responsive to said first induced impulse to close a circuit for said impulse repeating relay and responsive to said second induced impulse to open said circuit, damping means in the outgoing section for causing the two induced impulses in the incoming section to be of similar nature.

coming section to be of similar nature though opposite in direction, and means for disconnecting said damping means.

9. In a telephone system, a trunk line divided into sections inductively coupled, means for producing a direct current impulse in the outgoing section, said impulse causing a first induced impulse current in one direction and a second induced current impulse in the other direction in the incoming section, an impulse repeating relay, an impulse receiving relay responsive to said first induced current impulse to close a circuit for said impulse repeating relay and responsive to said second induced impulse to open said circuit, and damping means inductively coupled to said outgoing section for causing the two induced impulses in the incoming section to be of similar nature though opposite in direction.

10. In a telephone system, a trunk line divided into sections inductively coupled, means for momentarily causing a direct current flow in the outgoing section causing an induced impulse of one nature in the incoming section at the start of said direct current and an induced impulse of a different nature in the incoming section at the termination of said direct current in the outgoing section of said trunk line, an impulse repeating relay, an impulse receiving relay responsive to said first induced impulse to close a circuit for said impulse repeating relay, and responsive to said second induced impulse to open said circuit, and damping means inductively coupled to said outgoing section for causing the two induced impulses in the incoming section to be of similar nature though opposite in direction.

11. In a telephone system, a trunk line divided into sections inductively coupled, means for momentarily causing a direct current flow in the outgoing section causing an induced impulse of one nature in the incoming section at the start of said direct current and an induced impulse of a different nature in the incoming section at the termination of said direct current in the outgoing section of said trunk line, an impulse repeating relay, an impulse receiving relay responsive to said first induced impulse to close a circuit for said impulse repeating relay and responsive to said second induced impulse to open said circuit, and means controlled by said impulse repeating relay for reducing the current flow in its circuit after said circuit is established.

12. In a telephone system a trunk line having a circuit inductively coupled therewith, means for successively establishing and disrupting a direct current flow in said circuit, means for causing the rate of rise and the rate of decay of current in said circuit to be substantially the same, and a relay connected to said trunk line to respond to

- the impulses induced therein by the rise and fall of current in said circuit.
13. In a telephone system a trunk line having a circuit inductively coupled therewith, means for successively establishing and disrupting a direct current flow in said circuit, means for causing the rate of rise and the rate of decay of current in said circuit to be substantially the same, and a relay 10 connected to said trunk line to respond to the impulses induced therein by the rise and fall of current in said circuit, said relay being operated by one impulse and said relay having a locking winding effective 15 when the relay is operated to maintain the relay operated, said relay being deenergized and released by the succeeding impulse which is in the opposite direction to the preceding impulse.
14. Means for repeating impulses from a first circuit to a second circuit, said means including a relay which is operated and released by successive impulses of opposite polarity, means for sending one impulse to 20 said relay responsive to commencement of an impulse in the first circuit and for sending an impulse of opposite polarity to said relay responsive to the cessation of the impulse in the first circuit, and means for holding said relay in its operated position during the interval between impulses.

15. A relay having an operating winding and locking winding said operating winding being in a circuit which is inductively coupled with a second circuit, means for causing an increasing current flow in the second circuit whereby the relay is operated over the operating winding and locked over the locking winding and means for causing a decrease in the current flow in the second circuit whereby an opposing current flow is produced in the operating winding to release the relay.

16. A relay having a first and a second winding, means for producing a current flow in one direction in said first winding for operating said relay, means effective when the relay is operated for closing a locking circuit for the relay said locking circuit including the second winding, means effective when the relay is operated over the second winding for reducing the current flow through the second winding, and means for producing a current flow in the opposite direction in the first winding to deenergize 50 said relay, said locking circuit being opened thereby.

In witness whereof, I hereunto subscribe my name this 24th day of February, A. D. 1926.

ARTHUR FLAD.
